UNITED STATES PATENT OFFICE.

SAMUEL W. BURTCHAEELL, OF OAKLAND, CALIFORNIA.

APPARATUS FOR USE IN CEMENTING SOLES OR HEELS TO SHOES.

Application filed February 21, 1927. Serial No. 169,700.

In cementing soles or heels to shoes, various means have been employed for holding the sole or heel in its applied position to the shoe bottom until the cement has dried or set to firmly unite the sole or heel in place. One method has been to mount the shoe or upper on a last, cement and position the sole or heel thereon, and then to ensure a tight adhesion wrap elastic material over the sole or heel, passing the same beneath the last and in contact with the shoe upper. This method of application is extremely injurious to certain types of uppers often soiling the same, and in most instances, due to the action of the elastic and the period of time the pressure is maintained, injuriously creasing the upper. Another method has been practiced consisting of providing a special casting having a last incorporated therewith for mounting the shoe, the casting being clamped to a special support and having spaced below the last an arm for detachably receiving elastic members passed under tension over the sole or heel to be cemented. Such a device is expensive, two complete devices being necessary to expedite the work of applying soles or heels to a pair of shoes, and its use is injurious to the shoe upper as the elastic member is drawn over the shoe upper against the sole edge, stretching, wrinkling, and often soiling the same. This is due to the arm being of a width less than that of the last mounting the shoe.

The present invention relates more particularly to a means for use in cementing soles or heels to shoes, and which is adapted for cooperation with a shoe last, and is adapted for detachable association with a last jack. One of the objects of the invention is to provide a means for holding the sole or heel to the shoe bottom and which means is maintained under tension and is held out of contact with the shoe upper. Another object is to provide a structure adapted when in operation to be associated with the last and mounted on a last jack and to be removed from the jack with the shoe last and cooperate therewith both before and after in maintaining the cemented sole or heel in position until the adhesive has set. Another object is to provide a structure for association with a shoe last designed for mounting on a jack and which will preclude the elastic holding means cooperating with the sole or heel from contact with or in any manner injuring the shoe upper. A further object

is to provide a structure, the cost of which is only a trifle more than that of the present conventional cast shoe last, one which is simple in its operation, and which, when in use, is associated with a shoe last of conventional form and is capable of use with a conventional last jack. An important object is to provide a structure for use in the cementing of soles and heels to shoe bottoms and which may be purchased with but little cost by the shoe repairer, is adapted for use on the conventional last jack, and is capable of ready attachment to and detachment from the jack when desired.

In its broadest conception, the invention consists in associating with a conventional shoe last a member of a width and outline substantially corresponding to the width and outline of the foot portion of the last, and which member is adapted for projecting beneath the last to afford a means on which an elastic structure is anchored, which structure passes over the applied sole, and is held under tension, the last and member to facilitate their use and to render the jack usable for other purposes being adaptable for detachable association with a last jack.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

In the drawings forming a part of the invention:

Fig. 1 is a view in elevation of my invention in position on a jack.

Fig. 2 is a similar view with a shoe positioned on the last and elastic means holding the sole to the shoe bottom.

Fig. 3 is a view in transverse section on line 3—3 of Fig. 2.

Referring more particularly to the several views of the drawings wherein like characters of reference designate corresponding parts, 1 indicates a jack of the conventional form, on the upper end of which is removably mounted a body portion preferably of cast metal. The body comprises a solid or unitary heel portion provided with a recess

3 for receiving the upper end 4 of the jack 1 when the body is detachably positioned thereon. From the heel portion extends a sole last portion 5 of the conventional size 5 and shape employed in the shoe making or repairing trade, and over which sole last portion 5 and heel portion of the shoe to be repaired is adapted to be positioned in the usual manner. For convenience in description, the entire body 2 is hereafter referred to as a shoe last. Projecting forwardly from the heel portion of the last and lying in spaced relation below the sole last portion 5 is an arm 6. The longitudinal curve of 15 the under surface of the arm 6 corresponds substantially with the longitudinal curve of the upper surface of the sole last portion 5 and the peripheral edge of the arm 6 corresponds substantially to the outline of the 20 edge of the sole last portion 5. As illustrated, it is preferable that the width of the arm be substantially equal to the width of the sole last portion at a corresponding point, although, if desired, the width of the 25 arm at any corresponding point of the sole last portion may be greater. The objects of such construction of the arm will be presently pointed out.

With the body 2 or last mounted on the jack 1 as illustrated, the shoe to be repaired is positioned over the sole last portion 5 in the usual manner with the inner surface of the heel resting on the heel portion. With the sole cemented to the bottom of the shoe, 35 the same is held in position by an elastic member 7 until the uniting medium dries or sets. In applying the elastic member, the same is anchored at one end, and its free end is wrapped under tension over the sole 40 and under the lower face of arm 6 preferably for the full length of the sole, the end thereafter being anchored in any suitable manner. Maintaining the elastic member under uniform tension during its application ensures an even distribution of the 45 pressure over the sole for its full length. The portions of the elastic member extending between the sole and edge of the arm 6 are disposed at substantially right angles 50 to the sole edge and do not contact with the upper as would be the case if the arm was of a width narrower than the sole or sole forming last portion 5. If desirable heavy elastic bands may be substituted for the 55 single member 7, and their use enables their individual application and removal when

desired. With the sole held in position as illustrated and described, the body 2 is removed from the jack 1 and is laid to one side permitting new work to be carried on 60 by the workman on the jack and enabling the shoe with its newly applied sole or heel to be laid away in some convenient place until the adhesive means has set or dried.

I claim:—

1. A sole cementing apparatus comprising a last provided with a recess for detachably receiving a jack end, of means movable with the last and extending beneath the same in spaced relation thereto, said means being 70 of a general outline and contour of the last, and an elastic member cooperating with the means and extending over the upper surface of the last.

2. A sole cementing apparatus comprising 75 a last provided with a recess for detachably receiving a jack end, of means extending outwardly beneath the last in spaced relation thereto, and movable with the last to and from the jack end.

3. In combination with a last, an arm extending from the heel portion thereof forwardly beneath the last in spaced relation thereto.

4. In combination with a last, an arm integral with the heel portion thereof and extending forwardly therefrom to lie in spaced relation beneath the last, the width of the last and arm at corresponding points being substantially equal.

5. In combination with a last provided with a jack end receiving recess, an arm integral with the last and extending forwardly from the heel portion beneath the last in spaced relation thereto, the contour of the 95 undersurface of the arm corresponding substantially to the contour of the upper surface of the last.

6. In combination with a last provided with a jack end receiving recess, an arm 100 integral with the last and extending forwardly from the heel portion beneath the last in spaced relation thereto, the contour of the undersurface of the arm corresponding to the contour of the upper surface of the last, and the width of the last and arm at corresponding points being substantially equal.

In testimony whereof I have signed my name to this specification.

SAMUEL W. BURTCHAELL.
